UNITED STATES PATENT OFFICE.

CHARLES STOKES, OF PHILADELPHIA, PENNSYLVANIA.

BRICK.

SPECIFICATION forming part of Letters Patent No. 268,569, dated December 5, 1882.

Application filed June 1, 1882. (No model.)

To all whom it may concern:

Be it known that I, CHARLES STOKES, a citizen of the United States, residing in the city and county of Philadelphia, State of Pennsylvania, have invented a new and useful Improvement in Bricks for Advertising Purposes, which improvement is fully set forth in the following specification and accompanying drawings, in which—

10 Figure 1 is a face view of a brick embodying my invention. Fig. 2 is a vertical section thereof in line $\times \times$, Fig. 1. Fig. 3 is a view of a pavement illustrating the use of the invention.

15 Similar letters of reference indicate corresponding parts in the several figures.

My invention consists of bricks formed with letters or numbers which are adapted for advertising and ornamental purposes, said letters and ornamental characters being produced by inserting in the soft clay from which the bricks are made soft pieces of similar clay of different color of the shape of the letters or numbers, and then baking the molded clay as usual, the bricks thus being apparently homogeneous and of usual shape and size, with well-defined letters or numbers on their faces.

25 Referring to the drawings, A represents a brick, and B a letter, &c., on the face thereof.

30 In the formation of the brick the clay is molded as usual, and in one or both faces thereof I insert in a depression therein a letter or letters of the alphabet, or a number,

formed of the same clay, but of different color and in a soft condition, and then place the 35 brick in a kiln and burn it as usual, the effect whereof is to produce a well-defined letter or letters and number or numbers, and secure them in a firm and immovable manner to the brick as one solid body, the size and shape and 40 other features of the brick being the same as those in bricks in general use.

It will be seen that the inserted letter or number of each brick is flush with the exposed face thereof, and it wears away uniformly with 45 the body of the brick, so as to be continually exposed. The bricks as thus constructed are laid to form names, words, and numbers, which attract the attention of the passers-by, and thus constitute an interesting, inexpensive, 50 and durable method of advertising on the sidewalk, of which the inserted letters, &c., are an integral part.

Having thus described my invention, what I claim as new, and desire to secure by Letters 55 Patent, is—

The advertising-brick having a letter or number, which is previously formed of soft clay or earth similar to the brick, but of different color, inserted in the body of the brick and burned 60 with it, substantially as and for the purposes set forth.

CHARLES STOKES.
